UNITED STATES PATENT OFFICE.

HENRY BERNSTEIN, OF PHILADELPHIA, PENNSYLVANIA, ASSIGNOR TO
BERNSTEIN, KAUFMAN & CO., OF SAME PLACE.

DESIGN FOR BRAID.

SPECIFICATION forming part of Design No. 31,846, dated November 14, 1899.

Application filed October 19, 1899. Serial No. 734,131. Term of patent 3½ years.

To all whom it may concern:

Be it known that I, HENRY BERNSTEIN, a citizen of the United States, residing in the city and county of Philadelphia, State of Pennsylvania, have invented and produced a new and original Design for Braid, of which the following is a specification, reference being had to the accompanying drawings, forming part thereof.

10 The leading feature of my design for braid is a body formed of plaited stripes and brushes on said stripes.

Figure 1 represents a face view of a piece of braid embodying my design. Fig. 2 represents a section thereof on line x x , Fig. 1.

In the drawings, A designates a piece of braid, the body of which is composed of plaited stripes B and brushes C thereon.

Having thus described my invention, what I claim as new, and desire to secure by Letters 20 Patent, is—

The design for braid substantially as shown and described.

HENRY BERNSTEIN.
